VEHICLE DOOR LOCK

John V. Pastva, Jr., Parma Heights, Ohio, assignor to
The Eastern Company, Cleveland, Ohio

Filed May 18, 1973, Ser. No. 361,621

Term of patent 14 years

Int. Cl. D8—07

U.S. Cl. D8—109

FIG. 2

FIG. 1

FIG. 3

FIG. 4

FIG. 5

FIG. 6

FIG. 1 is a front elevational view of a vehicle door lock embodying my new design;

FIG. 2 is an end view of the lock looking into the left-hand end as viewed in FIG. 2;

FIG. 3 is an end view of the lock looking into the right-hand end as viewed in FIG. 2;

FIG. 4 is a top plan view of the lock;

FIG. 5 is a rear elevational view of the lock; and

FIG. 6 is a bottom plan view of the lock.

I claim:

The ornamental design for a vehicle door lock, substantially as shown.
